UNITED STATES PATENT OFFICE

RAYMOND R. RUNDELL, OF MIAMI, FLORIDA, ASSIGNOR TO HARRY BAKER, OF MIAMI, FLORIDA

SELF-CLOSING CAN TOP

Application filed March 21, 1927. Serial No. 177,173.

This invention relates to receptacles, cans, condiment holders, or the like, and more especially to the caps or closures for the perforated tops of said receptacles or cans.

5 The objects of the invention are:

First, to provide a closure of the character above indicated which will automatically open or expose the perforations or openings through which the contents of the receptacle 10 escape when said receptacle is turned upside down, or return said closure to its closed position when said receptacle assumes its normal position.

Second, to provide a closure of the character above indicated and operate in the manner above described which will consist of a minimum of parts, easily manufactured at a low cost, quickly assembled and at the same time constantly function under all conditions 20 of service.

Third, to provide a closure which will always after properly adjusting perform all the functions to automatically open and close the perforations through which the contents 25 of the receptacle escapes but at the same time is also adapted to be immovably held to lock the closure or cap in a fixed position and retain the contents within the receptacle whether the top of the receptacle is upwardly 30 or downwardly disposed, as during the shipment of said receptacles.

Fourth, to provide a cap or closure for a perforated top of a receptacle which will automatically seat itself to tightly seal all openings through which the contents of the receptacle pass, thereby preventing any access 35 of moisture or vermin into the interior of said receptacle when not in use.

Fifth, other objects and advantages of the 40 invention will appear from the detailed description of the several parts, manner of assembling the same and their cooperation.

The invention consists of structural characteristics and relative arrangement of the 45 several elements which will be hereinafter more fully described and particularly pointed out in the appended claims.

In the two sheets of drawings, in which 50 the same reference characters indicate the

same parts in the different figures of drawing.

Figure 1 is a vertical section of the top 55 of a receptacle provided with the improved closure;

Figure 2 is a top plan view of the cap or closure shown in Figure 1;

Figure 3 is a side elevation of the neck of the receptacle shown in Figure 1 with the closure or cap removed;

Figure 4 is an enlarged and developed sectional view taken on line IV—IV of Figure 3;

Figure 5 is a fragmentary and enlarged sectional view taken on line V—V of Figure 1;

Figure 6 is a top plan view of Figure 1 with 60 the cap or closure removed;

Figure 7 is a top plan view of a modified form of the cap or closure shown in Figures 1 and 2;

Figure 8 is a fragmentary view of a vertical section of a modified form of the cap or closure shown in Figures 1 and 2;

Figure 9 is a vertical section of a modified form of the invention shown in Figure 1;

Figure 10 is a fragmentary vertical section 75 view of the form shown in Figure 9 when the receptacle is inverted;

Figure 11 is a top plan view of Figure 10;

Figure 12 is a fragmentary side elevation 80 of the top of the receptacle shown in Figure 9 with its closure or cap removed;

Figure 13 is a top plan view of Figure 9 with the closure or cap removed;

Figure 14 is a vertical section of a further modified form of the invention, as shown in 85 Figures 1 and 9;

Figure 15 is a top plan view of Figure 14;

Figure 16 is a fragmentary and top plan view of Figure 14 when the cap or closure is shifted to permit the contents of the receptacle to escape; and

Figure 17 is a fragmentary side elevation 90 of the neck of the receptacle shown in Figure 14 with its cap or closure removed.

Referring to Figures 1, 2, 3, 4, 5 and 6, 20 is the body of the receptacle provided with a cylindrical hollow neck or upper section 21 having preferably a depressed or inverted conical top 22. Near the circular outer edge 100 of the top 22 adjacent the upper and outer

edge of the cylindrical hollow neck 21 is provided a series of separated and equally spaced openings or perforations 23, 23, through which the contents of the receptacle or can 20 can escape when said receptacle is turned upside down.

The exterior of the hollow cylindrical neck is provided with one or more depressions 24, each of said depressions 24 being formed with 10 a straight shallow vertical groove 25, a deeper and straight groove 26 oblique or inclined to said groove 25, and a shallower horizontal straight groove 27 having an offset portion 28, said grooves being connected to one another, as clearly shown in Figure 3.

29 is an annular cylindrical cap or closure which surrounds and loosely slides on the outer cylindrical wall of the hollow neck 21, and is provided on its inner wall with one 20 or more projections or tits 30 registering with and adapted to slide in the deeper inclined groove section 26 of the depressions 24, as shown in Figure 1. The top section, upper annular portion or edge 31 of the cap 25 or closure 29 is formed with a series of separated and inwardly projecting extensions 32, 32, preferably rectangular in shape and so spaced and of such number as to register with the openings or perforations 23, 23, 30 adjacent the upper and outer edge of the hollow neck 21, as shown in Figure 2.

The operation of the closure shown in Figures 1 to 6 inclusive, is as follows:

Assuming the parts having been assembled 35 as shown in Figure 1 and the interior of the body 20 of the receptacle having been filled with a powder, granular, or similar material and the receptacle is turned upside down, the weight of the loosely carried cap or 40 closure 29 will cause the same to slide down on the neck 21 and the projection or tit 30 engaging the oblique or inclined from the vertical groove 26, will cause said cap or closure 29 to rotate through an arc sufficiently to have the inwardly projecting extension 32, 32, of said closure to move laterally and uncover the openings or perforations 23, 23, and permit the contents of the receptacle to gravitate and escape through said 45 openings 23, and owing to the form of the inwardly projecting conical top 22, the contents of the receptacle are uniformly distributed and directed to said openings, as will be readily understood and need no further disclosure.

When it is desired to ship or pack the receptacle and prevent the unintentional egress or loss of material within the receptacle, the cap or closure 29 is non-rotatably locked on 50 the neck 21 by a partial rotation of said cap or closure on said neck, so that the projection or tit or tits 30 of the cap or closure at the bottom of the inclined groove 26 is forced into the groove 27 and frictionally engages its offset portion 28 and holds said closure or

cap 29 in the position with its extensions 32, 32, tightly clamped over perforations 23, as indicated in Figure 1, and prevents the escape of the material from the receptacle whatever position said receptacle may assume.

Figure 7 shows a plan view of a modified form of the cap or closure 29 shown in Figures 1 and 2, in that said closure or cap has the inner ends of the inwardly projecting extensions 321 connected by an annulus 323 integrally formed with said extensions 321, as shown, which makes a stronger and more permanent structure than that shown in Figures 1 and 2.

Figure 8 shows a fragment of a cover or closure 324 similar to that illustrated in Figures 1 and 2 except that the underside of each of the inwardly projecting extensions 325 is provided with a small protrusion 326 adapted to pass down into the perforations or openings 23 to not only more tightly seal said openings but at the same time dislodge any material which might stick in said openings and always keep the same clear for the proper flow and egress of the material from the receptacle when turned upside down, as heretofore explained.

Figures 9, 10, 11, 12 and 13 illustrate a further modification of the invention in which the neck 212 is provided with a depressed or inverted conical top 221 similar to that shown in Figure 1, except that the openings or perforations 231 and 232 are in the sides and apex of the cone surface as clearly shown in Figure 9. The cap or closure 292 of this form is provided with a conical inwardly projecting top 327 which seats itself into the conical top 221 and over the perforations 231 to close the same. A further difference from the cap or closure 29 shown in Figure 1 is that cap or closure 292 is provided with a series of separated openings or perforations 328 arranged just within the upper circular edge of said cap 292, as clearly indicated in Figure 9. The tits or projections 301 on said cap or closure 292 cooperate with depressions 241 in the neck 212 of the form and configuration as shown in Figure 12 with a slight sliding action of the closure 292 on the neck 212 while the tit 301 is in portion 261, and can be locked in position by having the projection or tit 301 engage the horizontal portion 271 of the depression 241 in the manner as explained with reference to Figures 1 to 6 and needs no further disclosure.

The manner in which the form of invention shown in Figures 9, 11 and 13 operates is as follows:

When the receptacle is inverted the top 327 of the cap or closure 292 drops and is separated from the inverted top 221 of the neck 212 into the position shown in Figure 10, which permits the material in the interior of the neck 221 to gravitate through the open-

ings 231 and thence out through the openings 328 in the path clearly indicated by arrows in Figure 10. When the receptacle is returned to its normal upright position the closure or cap 292 will again assume the position shown in Figure 9 and any material which might have accumulated or spilled into the conical chamber of the top 221 will pass down through the opening 232 in the apex of the cone and return to the interior of the neck 212 of receptacle and avoid any waste of said material.

The modification of the invention shown in Figures 14, 15, 16 and 17 is substantially the same as explained with reference to Figures 9, 10, 11, 12 and 13, except that the neck 413 of the receptacle is provided with an inverted conical top 422 having only a series of separated elongated openings or perforations 423 near the upper edge of the neck 413, as shown in Figure 14. The cap or closure 493 in this last form is provided with a conically shaped and inwardly projecting top 495 having a series of separated radially arranged ribs or spiders 496 separated by openings 497 and connected at their inner ends to an upturned and annular central section 498 provided with an opening 499, said ribs 496 being so disposed and arranged that when the cap or closure is in its lowest position on the neck 413, the ribs 496 are seated over and close the openings or perforations 423 in the conical top 422, as indicated in Figures 14 and 15. The partial rotation and locking of this cap or closure 493 is carried out substantially in the same manner as described with reference to Figure 3, in that the tit or projection 401, when the receptacle is inverted, slides in groove or depression 426, shown in Figure 17, and the cap or closure 493 is rotated sufficiently to assume the position shown in Figure 16 and uncover the openings 423, and in order to lock the cap 493, said projection 401 is slid and seated in the connected depression 427, and the ribs or spiders 496 are positioned and held over the openings 423, as indicated in Figure 14.

The operation of this last form is substantially the same as that described with reference to Figures 9 and 10, except that the material passes from the interior of the neck 413 out through the openings 423 and thence out through the openings 497 between the ribs 496, and should any of the material on the previous use have been spilled or deposited in the bottom of the conical top 422, said unused or accumulated material will pass down and through the opening 499, as will be readily understood.

It will thus be seen that the present invention, though simple and inexpensive to manufacture, fully and efficiently carries out all the functions and operations and has all the advantages recited in the statement of invention.

It is also obvious that many changes or modifications would readily suggest themselves or may be resorted to without departing from the spirit and essential features of the invention, and, therefore, I do not wish to be limited to the exact construction and arrangement therein shown and described.

What I claim is:

1. A receptacle comprising a body having a cylindrical hollow neck with a groove in the outer surface of its wall and a top having perforations for the outlet of the contents of the receptacle, an annular cylindrical closure or cap surrounding and loosely sliding on the cylindrical outer wall of said hollow neck and provided with imperforate inwardly projecting sections adapted to register with and cover the perforations of the top, and a projection on the inner side of said cap or closure within and engaging the groove in the outer surface of the wall of said neck to permit rotary as well as longitudinal movement of said cap or closure on said neck, said closure sliding downward with a slight rotary motion on said neck when the receptacle is inverted to uncover or expose said perforations and permit the contents of the receptacle to flow through said exposed perforations and escape from said receptacle.

2. A receptacle having a perforated top, a sleeve-like cap telescoping the receptacle and formed with lugs normally closing the perforations in said top, said cap having a loose fit on the receptacle such that it will slide by gravity to uncover the perforations when the receptacle is inverted, and means for limiting the sliding movement of the cap.

3. A receptacle having a perforated top, a sleeve-like cap telescoping the receptacle and formed with lugs normally closing the perforations in said top, said cap fitting loosely on the receptacle whereby it will slide by gravity to uncover the perforations when the receptacle is inverted, and means for limiting the sliding movement of the cap, said lugs having projections thereon adapted to enter said perforations.

4. A receptacle having a perforated top, a cap telescoping the receptacle and formed with lugs normally closing the perforations in said top, said cap having a loose fit on the receptacle such that it will slide by gravity to uncover the perforations when the receptacle is inverted, means for limiting the sliding movement of the cap, and means for securing the cap against sliding.

5. A receptacle having a perforated top, a cap telescoping the receptacle and formed with lugs normally closing the perforations in said top, said cap having a loose fit on the receptacle such that it will slide by gravity and uncover the perforations when the receptacle is inverted, and coacting means on

the receptacle and the cap for causing spiral movement of the cap when the latter slides.

6. A receptacle having a neck portion provided with an end wall, the latter being formed with perforations near the periphery thereof, a sleeve on the neck portion and formed at its outer end with closure means overlapping said wall and normally closing said perforations, the sleeve being mounted to slide freely on the neck in such direction that when the receptacle is inverted the sleeve will be moved by gravity to uncover said perforations, and means for limiting the sliding movement of the sleeve.

15 7. A receptacle having a neck portion provided with an end wall, the latter being formed with perforations near the periphery thereof, a sleeve on the neck portion and formed at its outer end with closure means overlapping said wall and normally closing said perforations, the sleeve being loosely mounted on the neck, whereby when the receptacle is inverted the sleeve will slide by gravity on the neck and uncover said perforations, and means for limiting the sliding movement of the sleeve, said closure means including projections adapted to enter the perforations when the receptacle is in normal position.

30 8. A receptacle having a cylindrical neck portion provided with an end wall, the latter being formed with perforations near the periphery thereof, a cap comprising a sleeve portion fitted over the neck portion and formed at its outer end with spaced, inwardly turned members overlapping said wall and normally closing said perforations, the sleeve being loosely mounted on the neck, whereby when the receptacle is inverted the sleeve will slide by gravity on the neck, and coacting stop means on the neck and sleeve portions respectively for limiting sliding movement of the sleeve, said stop means comprising a spiral groove in one of said portions and a tit on the other portion engaging and guided by the groove, whereby the sleeve will move spirally as it slides on the neck and said members will move laterally out of register with the perforations when the receptacle is inverted.

45 9. A receptacle having a cylindrical neck portion with an inverted conical top wall, the latter being formed with perforations near the periphery thereof, a cap comprising a sleeve portion fitted over the neck portion and formed at its outer end with spaced, inwardly-turned members adapted normally to overlie and close said perforations, the sleeve being loosely mounted on the neck whereby when the receptacle is inverted the sleeve will slide by gravity on the neck, and coacting stop means on the neck and sleeve portions respectively for limiting sliding movement of the sleeve, said stop means comprising a spiral groove in one of said

portions and a tit on the other portion engaging and guided by the groove, whereby the sleeve will move spirally as it slides on the neck and said members will move laterally out of register with the perforations when the receptacle is inverted, said groove having a shallow lateral extension into which said tit may be forced to hold the cap by friction against gravitational sliding movement.

10. A receptacle having a cylindrical neck portion with an outer end wall, the latter being formed with perforations near the periphery thereof, a cap comprising a sleeve portion fitted over the neck portion and formed at its outer end with spaced, inwardly-turned members adapted normally to overlie and close said perforations, the sleeve being loosely mounted on the neck whereby when the receptacle is inverted the sleeve will slide by gravity on the neck, and coacting stop means on the neck and sleeve portions, respectively, for limiting sliding movement of the sleeve, said stop means comprising a spiral groove formed in the neck portion and a tit in the sleeve portion engaging the groove whereby the sleeve will move spirally as it slides on the neck and said members will move laterally out of register with the perforations when the receptacle is inverted, said groove including a shallow extension through which the tit may be forced to apply or remove the cap from the receptacle, and said groove being also formed with a shallow lateral extension in which the tit may be forced to hold the cap against gravitational sliding movement.

In testimony whereof I hereunto affix my signature.

RAYMOND R. RUNDELL.
